UNITED STATES PATENT OFFICE.

THOMAS B. RICE, JR., OF PHILADELPHIA, PENNSYLVANIA.

SAFETY DEVICE FOR WOODWORKING-MACHINES.

SPECIFICATION forming part of Letters Patent No. 691,074, dated January 14, 1902.

Application filed August 31, 1901. Serial No. 73,904. (No model.)

To all whom it may concern:

Be it known that I, THOMAS B. RICE, Jr., a citizen of the United States, residing in the city and county of Philadelphia, State of Pennsylvania, have invented a new and useful Improvement in Safety Devices for Woodworking-Machines, of which the following is a specification.

My invention consists of a safety device for 10 woodworking-machines—for instance, sawing-machines, printing-presses, planers, and the like—the object being to provide a mechanism that automatically yields and stops the machine when a board of unusual size or shape 15 is encountered.

It further consists of novel details of construction, all as will be hereinafter set forth. It is understood, of course, that while I have 20 illustrated my invention as applied to a sawing-machine and have arranged the safety device to yield and to shift a belt from a fast to a loose pulley, yet it can be applied to other machines—such as planers, printing-presses, and the like—and may be arranged to 25 activate other means for regulating the power that drives the machine.

Figure 1 represents a side elevation of a sawing-machine to which my invention is applied. Fig. 2 represents a perspective view 30 showing the construction between the belt-shifting mechanism and automatic devices for operating the same. Fig. 3 represents a detailed perspective view of the belt-shifter. Fig. 4 represents a detailed side elevation 35 illustrating the passage of a board with a warped end. Fig. 5 represents a face view of the safety-gate and accompanying parts.

Similar letters of reference indicate corresponding parts in the figures.

Referring to the drawings, A designates a 40 sawing-machine which is of ordinary construction. The bed B of the machine is provided with a longitudinal slot or way C, within which the chain D travels, said chain being 45 provided with lugs or projections E and being driven by any suitable power—for instance, from the power-shaft F, carrying the fast pulley G and loose pulley H, by means of a belt J, extending to the shaft carrying the 50 saw K, and then by the belts L and M and the pulleys and gear shown. Mounted upon the bed B are the plates or guide N, between

which a plurality of boards P are stacked, and at the end of the said guide N, adjacent to the saw, is a gate Q, that is pivoted at its 55 upper end, so as to swing forward, as shown in Fig. 4. The lower edge of said gate Q is situated a little distance above the top of the bed B to provide sufficient space to allow the boards P to pass thereunder. Projecting outwardly from the gate is an arm R, and at the side of the bed is a pin S, upon which is hooked the bar T, said bar T having an eye at its end and being connected with the belt-shifter U by the connection V, that is trained over suitable pulleys W, as shown. Said connection 60 V is fastened to the slide X, that carries the belt-shifter U, while to the other end of the slide X a weight Y is fastened, which when the slide is released is heavy enough to draw 65 the slide to the left in Fig. 2 and shift the belt to the loose pulley H.

The operation is as follows: In the ordinary operation of the machine the bar T is hooked upon the pin S and the arm R of the gate is 70 below said bar T. In this position the belt J is on the fast pulley, and if the boards are of uniform thickness and shape the projections E of the sprocket-chain will successively 75 advance the lowermost board below the gate and to the saw K. If, however, a board is too thick or is warped or is fed incorrectly or for any other reasons contacts with the lower edge 80 of the gate Q, the advancement of said board will swing said gate on its pivot, as shown in Fig. 4, which will raise the arm R, and thus 85 disengage the bar T and pin S. Upon the disengagement of these parts the slide X is released and the weight will draw it to one side, thereby shifting the belt and stopping the operation of the machine.

It will be apparent that slight changes may be made by those skilled in the art which will come within the scope of my invention, and I do not, therefore, desire to be limited to the exact construction herein shown and described.

Having thus described my invention, what I claim as new, and desire to secure by Letters Patent, is—

1. In a machine of the kind specified, a 900 guide, a movable gate at one end thereof, an arm carried by said gate, fixed means on the frame of the machine, a bar having one end detachably and normally engaged over said

means, and extended over said arm, a belt-shifting mechanism and a connection between the same and the said bar, and means for actuating said shifting mechanism when the bar is released from its holding means by the upward movement of said arm.

2. In a machine of the kind specified, a guide mounted upon the bed thereof, a movable gate at one end of said guide, the lower edge of which is situated above said bed, an arm upon said gate, a pin upon the frame of

the machine, a bar engaging said pin and extending across the upper edge of said arm, a slide carrying a belt-shifter that engages the power-belt of the machine, a weight for moving said slide in one direction, and a connection between said slide and said bar. 15
